UNITED STATES PATENT OFFICE

ALBAN HAMELIN, OF MONTREAL, QUEBEC, CANADA

LAST

Application filed December 31, 1930. Serial No. 505,947.

The present invention relates to improvements in shoe lasts and has particular reference to that type of last embodying two or more adjustable sections.

- 5 A primary object of the invention is the provision of a shoe last of the above character embodying means for normally urging the connected last sections to an out of alignment position.
- 10 A further object of the invention is the provision of a shoe last of the above type having means for releasably locking the last sections in aligned working relation.

Another object of the invention is the provision of means for slidably connecting the component sections of the last in such manner as to permit rapid and convenient adjustment to a working or out of alignment position.

20 Still another object of the invention is the provision of a sectional last constructed so that the complementary sections will accurately maintain their relative positions.

Another object of the invention is the provision of a last of the above type which will be durable in construction and which can be manufactured at a relatively low cost.

Other objects and advantages of the invention will become apparent as the description progresses.

In the accompanying drawings forming a part of this specification and in which like reference characters are employed to designate corresponding parts throughout the same:

Figure 1 is a perspective view of the improved last construction.

Figure 2 is a side elevational view showing the last disposed in a shoe and arranged in working position.

Figure 3 is a side elevational view partly in section showing the respective last sections in out of alignment arrangement.

Figure 4 is a similar view illustrating the interior construction of the connecting means.

Figure 5 is a fragmentary side elevational view partly in section showing the respective last sections in aligned arrangement,

Figure 6 is an enlarged vertical section through the last connecting means, and

Figure 7 is a transverse section taken on the line 7—7 of Figure 6.

Referring to the drawings, wherein for the purpose of illustration is shown a preferred embodiment of the invention, the numeral 10 designates in its entirety a last adapted to be employed in the manufacture of boots and shoes, in the present instance divided on an inclined transverse plane to form a fore section 11 and a heel section 12. The inclined meeting faces of the sections 11 and 12 are provided with vertical centrally disposed grooves designed to accommodate therein the joining or connecting mechanism. Secured in the groove formed in the rear inclined face of the fore section 11 is an elongated slide bracket 14 of substantially U-shaped form in cross section. The web of the bracket 14 is rigidly fastened in the groove and is provided with an upper extension overlying the top face of the sections, as indicated at 15. The side flanges of the bracket are bent toward one another, as indicated at 16, so as to assume a converging relation toward the outer edges.

A complementary bracket 17 of similar construction is secured in the groove formed in the inclined face of the heel section 12, the outer edges of the opposed flanges of the two brackets being adapted to assume spaced parallel relation.

Secured in the lower portion of the bracket 14 is a slide block 19 of elongated form having V-shaped grooves formed in the opposed side faces so as to form, in cross section, a structure having a diminishing taper toward the centre. By thus constructing the slide block 19, the opposed portions are provided with an outwardly flaring taper disposed to snugly and slidably engage the slide brackets of each last section.

The lower block 19 is rigidly fastened in the bottom portion of the bracket 14 by means of a rivet 20 or other suitable fastener. The opposed portion thereof is disposed in and slidably engages the complementary bracket 17.

An upper slide bracket 21 is fitted in the upper portion of the bracket 17 and is rigidly

connected therewith by means of a rivet 22. The outer portion of the block 21 is in slideable engagement with the upper portion of the bracket 14.

Disposed between and connected with the inner end faces of the blocks 19 and 21 are coiled compression springs 24 tending to normally urge the last sections to offset positions out of working alignment.

The last sections may, however, be locked in working relation by means of adjustable locking mechanism embodying a latch bar 26 slidably disposed upon the upper face of the fore section 11 and slideable horizontally thereon.

15 The forward end of the bar carries a lip 27 for convenient adjustment thereof, while the rear end is engageable with a notch 28 formed in the upper portion of the block 21.

In use, prior to the insertion of the last 20 into a shoe, the latch bar 26 is manually actuated to a forwardly extended retracted position, disengaging the notch in the upper block 21 and permitting the coiled springs 24 to slide the fore and heel sections of the last to offset positions out of working alignment.

25 When thus arranged, the last may be quickly and conveniently inserted into the shoe. When the fore part is properly placed in the shoe upper, the heel section 12 is depressed into its proper relative aligned arrangement. The latch is then slid forwardly so that the rear extremity enters the recess 28 of the upper slide block and locks the sections in working position.

30 35 To remove the last from the shoe, the latch is again retracted and the heel section automatically elevated at a forwardly inclined angle so that the fore part may be conveniently removed from the shoe.

40 It is to be understood that the form of my invention herein shown and described is to be taken as a preferred example of the same, and that various changes as to the shape, size, and arrangement of parts may be resorted to 45 without departing from the spirit of the invention or the scope of the subjoined claims.

Having thus described my invention, I claim:

50 1. In a last, a pair of complementary transversely divided sections, a pair of complementary slide brackets secured to the adjacent faces of the sections, means in the brackets slidably connecting the sections together, 55 spring means normally urging the sections to positions offset from the normal working arrangement thereof, and an adjustable locking member operable to lock the sections in aligned working positions.

60 65 2. In a last including a pair of transversely divided sections, a pair of complementary slide brackets attached to the adjacent faces of the respective sections, slide blocks connected to the said brackets, and spring means disposed between the blocks adapted to resil-

iently urge the said sections to an offset arrangement.

3. In a last including a pair of transversely divided sections, a pair of complementary slide brackets attached to the adjacent faces 70 of the respective sections, slide blocks connected to the said brackets, spring means disposed between the blocks adapted to resiliently urge the said sections to an offset arrangement, and an adjustable locking member 75 engageable with one of the slide blocks to lock the sections in aligned working relation.

In witness whereof I have hereunto set my hand.
